DESIGN FOR A DRESS

Rubin Perlman, New York, N. Y.

Application December 17, 1937, Serial No. 73,668

Term of patent 3½ years

To all whom it may concern:

Be it known that I, Rubin Perlman, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the paisley dress disclosed, of the knife pleated skirt and draped bodice portion, as shown.

I claim:

The ornamental design for a dress, substantially as shown, and described.

RUBIN PERLMAN.
